UNITED STATES PATENT OFFICE.

JOHN J. SULLIVAN, OF IPSWICH, MASSACHUSETTS.

MACHINE FOR SEWING ON BUTTONS.

SPECIFICATION forming part of Letters Patent No. 595,742, dated December 21, 1897.

Application filed March 15, 1895. Serial No. 541,860. (No model.)

To all whom it may concern:

Be it known that I, JOHN J. SULLIVAN, a citizen of the United States, residing at Ipswich, in the county of Essex and State of Massachusetts, have invented certain new and useful Improvements in Button-Sewing Machines, of which the following is a specification, reference being had therein to the accompanying drawings.

10 My invention relates to a machine for sewing buttons to shoes or other articles to which it may be desirable to attach the same and in which is incorporated means controlled by the operator whereby buttons may be successively transferred from a button chute or guideway to the needle.

15 My invention is preferably applied to a machine having a stitch-forming mechanism comprising means for imparting horizontal movements to the needle-bar and needle, the machine in accordance with my invention having a feeding mechanism which operates at intervals to advance the work from one button-sewing position to another, my invention including means whereby the horizontal movements of the needle are suspended when the feeding mechanism is operating to advance the work, and the feeding mechanism being inoperative when the horizontal or over-seaming movements of the needle are occurring. In other words, the horizontal movements of the needle-bar and needle to form overseaming button-attaching stitches and the work-advancing movements of the feed 25 are alternated with each other, so that a button will be secured to the work by a suitable predetermined number of overseaming, stitches while the work remains stationary, and the overseaming movements of the needle-bar and needle will then be suspended, but without suspending their vertical movements, and the feed be thrown into operation to advance the work to a position for sewing on the next button; the button-attaching or overseaming stitches being thus practically a part 35 of a continuous seam extending from one button to another. As a predetermined number of stitches will be formed between the buttons, the distance apart of the latter will depend on the length of the plain stitches between the overseaming or button-attaching 40 stitches.

In the drawings, Figure 1 is a front side view of a "Singer" oscillating shuttle-arm or cylinder machine embodying my invention. 55 Fig. 2 is a rear side view of the same, partly in section. Fig. 3 is a front end view, and Fig. 4 a rear end view, of the same. Fig. 5 is a detail view on line xx , Fig. 3, looking down. Fig. 6 is a detail bottom view of the presser-foot, and 60 Fig. 7 a detail plan view of the button pusher or feeder. Fig. 8 is a plan view of the button reservoir or hopper, showing the button agitating or feeding brush within the same and the button-shank slot opening out into 65 the slot or groove of the button-chute; and Figs. 9, 10, and 11 are detail views to show the worm, worm cam-wheel, and connections between the latter and the feeding mechanism. 70

A denotes the base of the machine, from which extends forward the work-supporting horn or cylinder A', within which is the rocking shuttle-operating shaft a and the rocking feed-shaft a' , the latter carrying at its front 75 end the feed-dog a^2 . Surmounting the base A is the bracket-arm B, in the upper part of which is journaled the driving-shaft b , provided at its rear end with the pulley b' , having a clutch connection with said shaft by 80 means of the clutch-dog b^2 , which is mounted in the wheel or hub b^3 , fixed to said shaft, said dog being normally pressed forward into clutching engagement with the flange b^4 of said pulley by a coil-spring b^5 , interposed between a projection b^6 on said wheel or hub and said dog. At the rear of the bracket-arm B is a projection or bracket b^7 , within which is a vertically-movable stop-bar b^8 , pressed upward by a spring b^9 , but normally 85 held downward by a spring-pressed locking bolt or rod b^{10} , the rear end of which enters a notch in said bar, the forward end of said locking-rod being connected to the lower end of a tripping-lever b^{11} , operated, as hereinafter 90 described, to withdraw said rod from engagement with said stop-bar, when desired, to permit the spring b^9 to lift said bar so as to bring its upper end into the path of the clutch-dog b^2 to release the latter from clutching engagement with the flange b^4 of the pulley b' . Bearing against the upper end of the stop-bar b^8 is a stiff buffer-spring b^{12} , attached at 95 its lower end by a screw b^{13} to the projection 100

or bracket b^7 , said buffer-spring serving to cushion the impact and lessen the jar when the clutch-dog strikes the stop-bar and is in turn forced back into contact with the projection b^6 on the hub b^3 , the said stop-bar having a width less than its slideway in the bracket b^7 to permit it to move sidewise to a limited extent as the buffer-spring b^{12} yields when the machine is stopped.

10 C is the needle-bar, connected by a pitman c to a crank at the forward end of the driving-shaft b , said needle-bar carrying the usual eye-pointed needle c' and being reciprocated vertically in a horizontally-swinging frame c^2 , 15 pivotally mounted on center screws c^3 , so that the needle-bar and needle may be moved horizontally transversely of the work-supporting horn or cylinder A' or in the line of the feed of the work, which is across said horn or cylinder. 20 D is a cam-wheel having teeth d^9 at one portion of its periphery meshing with a worm b^{14} on the shaft b , said cam-wheel having in its front face a cam-groove d^2 , entered by a pin e on the lever E, pivoted at e' and connected by a pitman e^2 to the swinging needle-bar frame c^2 , said frame being thus operated by said cam-wheel. The said cam-groove has a concentric part d , and when this concentric part of said groove is passing the pin e the 25 swinging movements of the needle-bar frame, and consequently the horizontal movements of the needle-bar and needle, will be suspended and plain stitches will be made; but when the serpentine or irregular part d^2 of said cam-groove is passing said pin e the needle-bar and needle will be moved horizontally to form overseaming or button-attaching stitches, the number of these overseaming or button-attaching stitches made at each rotation of 30 said cam-wheel depending on the number of curves or cam-points in the said cam-groove. 35

The feed rock-shaft a' is operated in the manner usual in the well-known Singer lock-stitch machines from the cam b^{15} on the shaft b through the feed connection or lever b^{16} , the lower end of which is jointed to an arm at the rear end of said rock-shaft. The lever b^{16} is connected by a link b^{17} with the usual feed-regulator of the Singer machine, this feed-regulator consisting of a short shaft f , having an arm f' , to which the lower end of said link b^{17} is jointed at f^3 , and a second arm f^2 , which may be moved up and down to change the relation of the toggle (consisting of the arm f' and link b^{17}) to the lever b^{16} to vary the up-and-down movement imparted to said lever or feed connection by the cam b^{15} , the position of the joint f^3 between the arm f' and the link b^{17} determining the length of the feed, 45 the feed being diminished by bringing the link b^{17} nearer parallel to the lever b^{16} and being increased by changing the regulator so as to throw the lower end of said link away from said lever, as is usual with this toggle-feed. 50

65 To entirely arrest the operation of the feed when the overseaming or button-attaching stitches are being formed, I provide a feed-

suspending device consisting, as herein shown, of a bell-crank lever, one arm, g , of which is provided with a pin g^6 , entering a cam-groove d' in the periphery of the cam-wheel D. The other arm, g' , of said lever carries a pin g^3 , connecting said arm g' to a lever g^8 , pivoted at g^4 to a bracket g^5 , rigid with the bracket-arm B, the slotted inner or free end 70 of said lever g^8 embracing a pin f^4 on the arm f^2 of the feed-regulator. By the connection just described of the feed-suspending lever with the feed-regulator it results that when in the rotation of the cam-wheel D the serpentine or acting part d^2 of the face cam-groove therein is just passing by the pin e , so that the horizontal movements of the needle-bar and needle are to be suspended, an operating part of the cam-groove d' in said cam-wheel acts on the pin g^6 in the arm g of the feed-suspending lever and causes said lever to so change the position of the feed-regulator as to set the feed (which had been arrested while the overseaming or button-attaching stitches were being formed) into operation, and just as the serpentine or acting part d^2 of the said face cam-groove again reaches the said pin e the cam-groove d' again changes the position of the feed-suspending lever and throws the feed out of action. Thus the feeding movements of the feed-dog and the overseaming movements of the needle-bar and needle will be alternated with each other, so that a series of overseaming or button-attaching stitches will be made when the work is at rest and a series of plain stitches will be made when the work is fed to space the buttons. 80

The cam-wheel D carries a pin d^7 , which is so arranged on said wheel that when the cam-groove d' has acted on the feed-suspending lever and the feed has been stopped said pin will engage the tripping-lever b^{11} to cause the latter to withdraw the locking bolt or rod b^{10} from engagement with the stop-bar b^8 , and thus permit the spring b^9 to throw said bar upward into the path of the outer end of the clutch-dog b^2 to disengage the said dog from the pulley b' , and thus stop the machine. 90

The worm-operated cam-wheel D is intermittently rotated—that is to say, the movement of said worm-wheel imparted thereto at each rotation of the driving-shaft is effected during a partial revolution of said shaft—so that the horizontal movements of the needle-bar will take place while the needle is out of the work, this result being accomplished in a well-known manner by giving the worm b^{14} an irregular pitch instead of a regular screw-pitch. With the use of a worm b^{14} having a certain pitch a certain number of stitches will be formed at each revolution of the worm cam-wheel D, these stitches being divided into plain and overseaming stitches according to the relative lengths of the serpentine and concentric parts of the cam-groove d^2 . As a certain predetermined number of plain stitches will thus be formed between the but- 100 105 110 115 120 125 130

tons the distance apart of the latter will depend on the length of these plain stitches, and it is for the purpose of governing the lengths of these plain stitches that the feed-suspending lever is indirectly connected with the feed-regulator through the lever g^3 . The pin g^2 is adjustable in the slot in the arm g' of the feed-suspending lever and also in the slot of the lever g^3 , so that by changing the position of this pin g^2 relative to the fulcrum-points of these levers the outer end of the arm f^2 of the feed-regulator (where the pin f^4 , acted on by the lever g^3 , is located) will be left higher or lower, as may be desired, when the feed-regulator is moved to throw the feed into action, and thus the length of the feed will be greater or less, according to the distance apart at which it may be desired to space the buttons. The higher the outer end of the arm f^2 is raised the more the lower end of the link b^{17} will be moved out of line with the lever b^{16} and the greater the length of feed will be, and vice versa.

H denotes a receptacle or hopper for holding the buttons, and H' is a stationary or fixed raceway or chute which conducts the buttons from said hopper to a point adjacent to the needle. Connected with the cam-wheel D, to rotate therewith, is a bevel-gear d^3 , meshing with a bevel-gear d^4 on a short vertical shaft d^5 , extending up into the hopper H and having attached to its upper end a button stirring or agitating device, consisting, preferably, of brushes d^6 . The bottom of the hopper is provided with a slot h to receive the shanks of the buttons, said slot opening at the outer edge of the bottom of the hopper into a slot or groove h' , formed in the chute H', so that buttons whose shanks have been entered into the said slot h may be forced outward into said chute by the agitating device or brush d^6 . The chute H is provided at its lower end with a spring h^2 , which prevents the buttons from escaping at improper times from said chute, the latter, as herein shown, terminating at one side in a curved finger h^3 .

I is the presser-foot provided with a curved finger i , which is arranged above and slightly separated from the finger h^3 , so that between these two parts will be left an opening forming a continuation of the shank-receiving groove or slot h' of the chute H', and thus the shanks of the buttons can pass beneath said finger i when forced to the needle, the presser-foot having in its bottom a curved recess i^2 , which receives the heads of the buttons.

Adjacent to the lower end of the button-chute is a swinging button-transferring device or pusher k , the shank of which has a vertical pivot k' journaled in the bracket b^{19} , suspended from the head at the forward end of the bracket-arm B of the machine, said button-pusher being connected by a rod k^2 , attached at one end to an arm k^3 on said pivot k' , to the upper end of a lever m , joined at its lower end by a link m' to an arm n of

a rock-shaft N, extending transversely of the base A and having a second arm n' , to which is attached a treadle-operated rod L. The rod k^2 is provided with two collars k^3 k^4 , and the lever m has at its upper end an eye or loop m^2 , which loosely embraces said rod. The said eye or loop m^2 is contiguous to the collar k^3 ; but between said eye or loop and the collar k^4 is a spiral spring k^5 . Attached to the lower end of the stop-bar b^8 is a rod k^6 , having a loop k^7 extending beneath the arm n' , to which the treadle-rod L is attached, so that when said arm is depressed it will engage said loop and thus draw down the stop-bar b^8 and thereby disengage its upper end from the clutch-dog b^2 to permit said clutch-dog to be thrown by the spring b^5 into holding engagement with the continuously-rotating or power-driven pulley b' to connect said pulley with the driving-shaft b to start the machine. The treadle-rod L is to be connected with an ordinary sewing-machine heel-and-toe treadle, so that it may be lowered or raised positively. When a button is to be transferred from the button-chute H' to the needle, the operator depresses the treadle-rod L, connected, as above described, to the button-pusher k , causing said pusher to act on the lowermost button in said chute and force the same outward, the button-head being guided in its outward movement by the curved recess i^2 in the bottom of the presser-foot I and the curved finger i , so that the shank of the button will be brought into such position that when the needle resumes its overseaming or horizontal movements it will descend alternately into and outside of the eye of said shank, so as to attach the button to the work by overseaming-strokes.

When the machine has been stopped and before it is again started, a button is to be transferred from the button-chute to sewing position. To provide for this operation and to permit the button-pusher and the start-motion device to be operated from one movement of the treadle-rod, the spring k^5 , interposed between the eye or loop m^2 of the lever m and the collar k^4 on the rod k^2 , is stiff enough to operate the button-pusher to transfer the button to the needle without being compressed appreciably; but after the button has been forced into sewing position and the forward movement of the button-pusher has been stopped, by positive contact of the button with the presser-foot or other fixed part, a still further downward movement of the treadle-rod is necessary to fully disengage the stop-bar b^8 from the clutch-dog b^2 , and in this further downward movement of the treadle-rod the spring k^5 becomes compressed between the eye or loop m^2 and the collar k^4 . The collar k^3 is provided with a projection k^9 , which in the backward movement of the rod k^2 engages a stop device or pin a^4 on the housing a^5 , inclosing the worm cam-wheel D, so that the backward move-

ment of the button-pusher and the upward movement of the treadle-rod L will be thus positively limited or stopped.

The general operation of my machine is as follows: Buttons being supplied to the hopper H and the chute H' and the work being placed beneath the presser-foot the operator depresses the treadle-rod, and the downward movement of said rod first operates the button-pusher to transfer a button from the lower end of the button-chute to sewing position beneath the needle, and a continued downward movement of the treadle-rod disengages the stop-bar b⁸ from the clutch-dog b² to start the machine, which commences to sew by overseaming or button-attaching stitches, the serpentine or operating part d² of the cam-groove d d² being at this time passing the pin e, so as to impart horizontal movements to the needle-bar and needle, and when these horizontal movements cease the feed, which had meanwhile been idle, is thrown into operation to advance the work and make plain stitches, as hereinbefore described. When a proper number of the latter have been made, to bring the work into position for the next button the cam-groove d' acts on the feed-suspending lever g g' to throw the feed out of operation, and at the same time the pin d⁶ on the cam-wheel D engages the tripping-lever b¹¹ to withdraw the locking-bolt b¹⁰ from engagement with the stop-bar b⁸, so that said bar is now free to be shot upward by its spring b⁹ into the path of the clutch-dog b² to stop the machine. Thus with a machine constructed as hereinbefore described the work may continue, the buttons being transferred from the button-chute to the needle by the treadle-operated button pusher or feeder, and the machine being automatically stopped when the work has been fed, and the machine will again be started by the operator by the same treadle-rod which operates the said button pusher or feeder. It is, however, not necessary that the machine should be stopped for each button sewed on, as the treadle-rod L may be depressed by the operator to transfer a button from the button-chute to sewing position while the work is being fed and plain stitches are being formed, and if the said treadle-rod be held depressed when the tripping-lever is operated to withdraw the locking-bolt from the stop-bar the latter will be held from shooting upward to stop the machine. If the treadle-rod be thus held depressed at the time when the feed of the work ceases, the overseaming or lateral movements of the needle will be resumed without cessation of the operation of the machine, and the needle, which in making plain stitches was too far toward the operator to enter the eye of the button-shank, will in its overseaming movements descend alternately into and outside of said eye to attach the button to the work. Thus my improved machine, although organized to stop at each button, may nevertheless be oper-

ated continuously until a whole set of buttons has been sewed to a button-piece.

Although I have herein shown the non-automatic button-feeder k, which serves to transfer the buttons successively from the lower end of the fixed or stationary button chute or guideway H' to sewing position, as being adapted to be pedal-operated by means of the treadle-rod L, I do not wish to be understood as limiting the non-automatic button-feeding feature of my invention to a pedal-operated button-feeder, as this non-automatic feeder may be actuated by the knee or hand of the operator, if desired, by substituting an ordinary knee-lever, such as is in common use for lifting the presser-feet of sewing-machines for the treadle-rod, or by moving the feeder manually. In fact, the button-feeder of my machine herein shown and described has already been successfully operated manually without the treadle-rod L, the operator each time a button was to be transferred from the button-chute to the needle merely pressing down with his thumb or fingers on the outer end of the arm n' of the rock-shaft N.

Having thus described my invention, I claim and desire to secure by Letters Patent—

1. In a button-sewing machine, the combination with a stitch-forming mechanism and an automatic feeding mechanism for advancing the work to space the buttons, of a fixed or stationary button chute or guideway the lower end of which extends to a point closely adjacent to the work-plate, and a pedal-actuated button-feeding device located at said lower end of said chute and by means of which the operator may transfer buttons from said chute to sewing position.

2. In a button-sewing machine, the combination with a stitch-forming mechanism, of an automatic feeding mechanism for advancing the work to space the buttons, button-feeding appliances comprising a stationary or fixed button chute or guideway and a button-feeding device for transferring buttons from said chute to sewing position, and an automatic stop-motion mechanism normally acting to suspend the operation of the machine after each button has been attached.

3. In a button-sewing machine, the combination with a stitch-forming mechanism, of an automatic feeding mechanism for advancing the work to space the buttons, button-feeding appliances comprising a stationary or fixed button chute or guideway and a button-feeding device for transferring buttons from said chute to sewing position, an automatic stop-motion mechanism normally acting to suspend the operation of the machine after each button has been attached, and a controlling device by which the operator may, when desired, suspend the action of the said stop-motion mechanism so that the machine will run continuously to sew on a series of buttons.

4. In a button-sewing machine, the combination with a stitch-forming mechanism, of an automatic feeding mechanism for advancing the work to space the buttons, a stationary or fixed button chute or guideway, a non-automatic or operator-actuated button-feeder for transferring buttons from said chute or guideway to sewing position, and an automatic stop-motion mechanism normally acting to stop the machine after each button has been attached.

5. In a button-sewing machine, the combination with a stitch-forming mechanism, of an automatic feeding mechanism for advancing the work to space the buttons, a stationary or fixed button chute or guideway, a pedal-operated button-feeder for transferring buttons from said chute or guideway to sewing position, and an automatic stop-motion mechanism normally acting to stop the machine after each button has been attached.

6. In a button-sewing machine, the combination with a stitch-forming mechanism, of an automatic feeding mechanism for advancing the work to space the buttons, a button chute or guideway, a non-automatic or operator-actuated button-feeder for transferring buttons from said chute or guideway to sewing position, an automatic stop-motion mechanism normally acting to stop the machine after each button has been attached, and a controlling device by which the operator may, when desired, suspend the action of the said stop-motion mechanism so that the machine will run continuously to sew on a series of buttons.

7. In a button-sewing machine, the combination with a stitch-forming mechanism, of an automatic feeding mechanism for advancing the work to space the buttons, a stationary or fixed button chute or guideway the lower end of which extends to a point closely adjacent to the work-plate, a button-feeder located at the lower end of said button-chute, and means whereby said feeder may be actuated by the operator to transfer buttons from said chute or guideway to sewing position relative to the needle and work-plate.

8. In a button-sewing machine, the combination with a stitch-forming mechanism and a fixed or stationary button chute or guideway, of a horizontally-movable, pedal-operated button-feeder located at the lower end of said chute and serving to transfer buttons from the latter to sewing position, and an automatic feeding mechanism for advancing the work to space the buttons.

9. In a button-sewing machine, the combination with button-feeding devices, of a stitch-forming mechanism comprising a horizontally-movable needle-bar and needle and an automatic feeding mechanism, independent of said needle-bar and needle, for advancing the work to space the buttons, of an automatic mechanism acting to suspend the horizontal movements of the needle and the work-advancing action of the feed alternately, to

form overseaming or button-attaching stitches when the work is at rest and plain stitches between the buttons.

10. In a button-machine, the combination with a stitch-forming mechanism comprising a needle and means for imparting vertical and horizontal movements thereto, of an independent automatic work-feeding mechanism, automatic devices for presenting buttons to the said needle, a needle-bar-controlling cam by which lateral movements are imparted to the needle-bar and needle, when desired, and which also serves to suspend the said horizontal movements, and a feed-controlling cam to throw the feed into and out of operation, said cams being so timed relative to each other that when the horizontal movements of the needle are suspended the feeding mechanism is operative, and when the feeding mechanism is inoperative, horizontal movements will be imparted to the said needle-bar and needle.

11. In a button-sewing machine, the combination with a stitch-forming mechanism, of a button receptacle or hopper having a curved slot or recess in its bottom and within the periphery of the latter, for the reception of the shanks of the buttons, a button-chute having also a button-shank groove or recess into which the said slot or recess in the bottom of the hopper opens, and a button-stirring device or pusher within said hopper serving to force the buttons outward from said hopper into said chute with their shanks in the groove or recess of the latter.

12. In a button-sewing machine, the combination with a stitch-forming mechanism, of an automatic feeding mechanism for advancing the work to space the buttons, a stationary or fixed button-chute, a button-feeder controlled by the operator and serving to transfer the buttons successively from said chute to the needle, and a start-motion device connected with said button-feeder and acting to set the machine in operation by a continuation of the same movement which feeds up a button.

13. In a button-sewing machine, the combination with a stitch-forming mechanism comprising a horizontally-movable needle-bar and needle, of a button-feeding mechanism which brings the buttons to such position relative to said needle that the latter will pass through the eye of a button when the needle is in one of its horizontal positions, but will pass outside of the said eye when in its other horizontal position, an automatic feeding mechanism independent of the needle-bar and needle for advancing the work, and means for alternately suspending and throwing into action the horizontal movements of the needle and the operation of the feed, the needle being in such position, when the feed is operating, as to pass outside of the eye of a button-shank which is in sewing position.

14. In a button-sewing machine, the combination with a stitch-forming mechanism, of a

fixed or stationary button-chute, as H', the horizontally-movable button-feeder k for transferring buttons from the lower end of said chute to the needle, the rod k² for operating said feeder, the lever m, the link m', the rock-shaft N having arms n and n', and the treadle-rod L connected to said arm n'.

15. In a button-sewing machine, the combination with a stitch-forming mechanism, of a fixed or stationary button-chute, the horizontally-movable button-feeder k located at the lower end of said chute and serving to transfer buttons from the latter to the needle, the rod k², the lever m yieldingly connected to said rod by an interposed spring, the rock-shaft N having arms n and n', a treadle-rod L connected to said arm n', and a start-motion device constructed and arranged to be actuated to set the machine in operation, by 20 a continuation of the same movement of the said arm n' which is required to operate the said button-feeder in feeding a button to the needle.

16. In a button-sewing machine, the combination with a stitch-forming mechanism comprising a horizontally-movable needle-bar and needle, of the intermittently-rotated cam-wheel D having a feed-controlling cam, as d', and having also a needle-bar-controlling cam 30 consisting of a concentric or non-operative cam-groove, or part d and a serpentine or operative groove or part d², connections between said cam-wheel and needle-bar whereby the latter may be moved laterally when desired, 35 a feeding mechanism, and connections between the latter and said feed-controlling cam, the latter acting to set the feed into action and to suspend its operation, alternately.

17. In a button-sewing machine, the combination with the driving-shaft thereof, a stitch-forming mechanism operated from said shaft, and button-feeding appliances, of a stop-motion device consisting of the loose pulley b' having the flange b⁴, the spring-pressed clutch-dog b², the wheel or hub b³ fixed to said shaft and in which said clutch-dog is mounted, the stop-bar b⁸, a spring for forcing the latter toward the path of movement of said clutch-dog, a locking rod or bolt serving to hold said 45 stop-bar away from said dog, a spring which presses said locking rod or bolt toward said stop-bar, and an automatic tripping device acting in opposition to the stress of the locking rod or bolt pressing spring and by which 50 said bolt may, at proper times, be withdrawn from said stop-bar.

18. In a button-sewing machine, the combination with the driving-shaft thereof, a stitch-forming mechanism operated from said shaft, 60 and button-feeding appliances, of a stop-motion device consisting of the loose pulley b' having the flange b⁴, the spring-pressed clutch-dog b² engaging said flange, the wheel or hub b³ fixed to said shaft and in which said 65 clutch-dog is mounted, the stop-bar b⁸, a spring

for forcing the latter toward the path of movement of said clutch-dog, a locking rod or bolt serving to hold said stop-bar away from said dog, a spring which forces said rod or bolt toward said stop-bar, an automatic tripping device acting in opposition to the stress of the locking rod or bolt pressing spring and by which said rod or bolt may, at proper times, be withdrawn from said stop-bar, and a buffer-spring, as b¹², to cushion the impact and lessen the jar when the machine is stopped. 70

19. In a button-sewing machine, the combination with the driving-shaft thereof, a stitch-forming mechanism operated from said shaft, and button-feeding appliances, of a stop and start motion device consisting of the loose pulley b' having the flange b⁴, the spring-pressed clutch-dog b² engaging said flange, the wheel or hub b³ fixed to said shaft and in which said clutch-dog is mounted, the stop-bar b⁸, a spring for forcing the latter toward the path of movement of said clutch-dog, the locking rod or bolt b¹⁰ adapted to engage said stop-bar and hold the latter away from said clutch-dog, a spring which forces said rod or bolt toward said stop-bar, the tripping-lever b¹¹ connected to one end of said locking rod or bolt, a rotary device to engage said tripping-lever and move the same in opposition to the pressure of the said last-named spring 95 when the machine is to be stopped, and means, controlled by the operator, whereby said stop-bar may be withdrawn from engagement with said clutch-dog when the machine is to be started. 100

20. In a button-sewing machine, the combination with the driving-shaft thereof, a stitch-forming mechanism operated from said shaft, and button-feeding appliances, of a stop and start motion device consisting of the loose pulley b' having the flange b⁴, the spring-pressed clutch-dog b², the wheel or hub b³ fixed to said shaft and in which said clutch-dog is mounted, the stop-bar b⁸ provided with a rod k⁶ having the loop or part k⁷, a spring for forcing said stop-bar toward the path of movement of said clutch-dog, the locking rod or bolt b¹⁰ adapted to engage said stop-bar and hold the latter away from said clutch-dog, a spring which forces said rod or bolt toward said stop-bar, the tripping-lever b¹¹ connected to one end of said locking rod or bolt, a rotary device to engage said tripping-lever and move the same in opposition to the stress of said last-named spring when the machine is 110 to be stopped, the rock-shaft N having the arm n' to engage said loop or part k⁷, and a treadle-operated rod L for actuating the said arm n'. 115

In testimony whereof I affix my signature 125 in presence of two witnesses.

JOHN J. SULLIVAN.
